ATTACHMENT FOR CLOSING DEVICES

Storrs M. Bishop, Schenectady, N. Y.

Application November 27, 1934, Serial No. 754,993

3 Claims. (Cl. 20—67)

This invention relates to devices for closing openings between two relatively movable objects and it has for an object the provision of a simple, inexpensive, reliable and improved device of this character.

More specifically the invention relates to anti-draft devices for preventing the passage of air currents through the space between the bottom of a door and the floor of a dwelling house and the like. Due to the increasing utilization of thermostats to control the heating systems of modern dwelling houses, it is becoming increasingly important to prevent the passage of cold air currents from bed-rooms into the remainder of the house, lowering the temperature and causing the thermostat to respond to open the furnace drafts and thus waste fuel.

Devices heretofore utilized for this purpose have been subject to rapid wear, and loss of efficiency necessitating frequent replacement. Accordingly a further object of this invention is the provision of an anti-draft device which is maintained out of engagement with the floor during the opening and closing movements of the door so that wear and consequent loss of efficiency are substantially eliminated.

A still further object of the invention is the provision of a device of this character which is easily applied or removed from a door and which by a very slight change may be applied either to a right or left hand door.

In carrying the invention into effect in one form thereof a sealing member is attached to the door by suitable fastening means which provide for movement of the member with respect to the door, and means are provided for actuating this sealing member into engagement with both the floor and the door when the door is closed, together with means for automatically actuating the sealing member out of engagement with the floor during its opening and closing movements.

For a better and more complete understanding of the invention reference should now be had to the following specification and to the accompanying drawing, in which Fig. 1 is a broken view in perspective of a dwelling house door with the anti-draft device of the invention applied thereto; Fig. 2 is a horizontal section of the door of Fig. 1 taken on a line between the knob and the floor illustrating the operation of the device; Fig. 3 is a side elevation partly in section illustrating the attachment of the sealing member to the door and the manner in which the sealing member is retracted from engagement with the floor when the door is open; Fig. 4 is a view

similar to Fig. 3 illustrating the manner in which the device operates to close the opening between the bottom of the door and the floor when the door is closed; Fig. 5 is a detailed sectional view illustrating the manner of attaching a resilient fabric-like member to the rod; and Fig. 6 is a sectional view similar to Fig. 3 illustrating the reversibility of the device for application to a right-hand door.

Referring now to the drawing, a doorway such for example as the doorway into the bedroom of a dwelling house is adapted to be closed by a door 10 which is mounted for pivotal movement on hinges 11. The usual lateral door stops 12 and 13 are provided. These stops serve to limit the movement of the door and to provide a tight joint between the door and the jambs 14 and 15.

For the purpose of tightly closing the opening between the bottom edge of the door 10 and the floor 16 to prevent the passage of air currents when the door is closed, suitable sealing means, illustrated as a rod-like member 17 is provided. Although this member may be made of any suitable material, it is preferably made of some inexpensive material such as wood. It is preferably round in cross-section and of sufficient diameter to insure the necessary rigidity. A diameter of $\frac{5}{8}$ " is usually sufficient. The length of the rod member 17 is substantially the width of the door 10 less the combined thickness of the two door stops 12 and 13.

A longitudinal strip of felt 18, cloth or other suitable resilient material is attached to the rod member 17 by any suitable fastening means illustrated as small nails 19. The strip has a width slightly more than the diameter of the rod so that it will engage the floor 16 and the face of the door 10 when the latter is closed as illustrated in Fig. 4.

Suitable means illustrated as a pair of hooks 20 and 21 and a cooperating pair of eye members 22 and 23 are provided for movably mounting the rod member on the door 10. The eye members 22 and 23 are screwed into the rod member, as illustrated, at a point with respect to the center line 24 such that when the rod member is in the position illustrated in Fig. 4 the felt will be in contact both with the floor and the face of the door. The hook members 20 and 21 are screwed into the door at a predetermined distance above the floor. This distance is of course determined by the dimensions of the rod 17 and the hooks and eyes and is so determined that when the eye member 22 is in the position on the shank of the hook 20

illustrated in Fig. 3, the rod 17 will be lifted out of engagement with the floor by the distance x and also retracted from engagement with the door, whereas when the eye member 22 is in the position on the shank of the hook illustrated in Fig. 4 the rod will engage both the floor and the face of the door as indicated. The hook 20 farthest away from the hinges has a shank which has a slight amount of upward curvature gradually merging into the more sharply curved or hooked portion. The hook 20 is further provided with a fixed cup-shaped washer 24 which determines the distance the hook is screwed into the door, and with a loose cup-shaped washer 25. As shown, the loose washer 25 is located on the hook 20 between the eye member 22 and the fixed washer 24, and both washers 24 and 25 are arranged with their cupped interiors facing each other and their backs abutting against the door 10 and the eye member 22 respectively. The hook 21 is an ordinary hook cooperating with the eye 23 in the usual manner.

Suitable resilient means, illustrated as a coiled compression spring 26 surrounding the shank of the hook 20 between the washers 24 and 25, is provided for moving the eye member 22 and the sealing member 17 upwardly along the curved shank of the hook. This spring has a length and a compression force just sufficient to actuate the sealing member 20 to the position away from the door and above the floor illustrated in Fig. 3 when the door is open.

For the purpose of actuating the sealing member into engagement with the floor and the door when the latter is closed, suitable means illustrated as an angle member 27 are provided. This angle member has a base portion which is secured by suitable fastening means 28 to the end of the sealing member farthest from the door hinges and a plate portion 27a substantially at right angles with the base portion which engages the stop 12 in the nearly closed and closed positions of the door.

From the foregoing description, it will be seen that the device is composed of simple, inexpensive parts and that it may be easily installed on any door without requiring the exercise of any skill.

With the foregoing understanding of the elements and their organization, the operation of the completed device will readily be understood from the following description:

When the door 10 is open the parts are in the position illustrated in Fig. 3 with the sealing member 17 positioned well above the floor and away from the door 10.

As the door is closed, it approaches the stop 12 diagrammatically represented in Figs. 3, 4 and 6 by the dotted line. In the nearly closed position of the door illustrated in Fig. 3, the lower edge of the plate portion 27a of the angle member is just engaging the stop 12. As the closing movement progresses the shank of the hook 20 slides through the movable washer 25 and eye 22, thereby compressing the spring 26, the force of which against the eye member 22 rocks or rotates the sealing member in a clockwise direction about the edge 27a of the angle member as a pivot. In the fully closed position of the door 10, the spring 26 is fully compressed and the member 17 is rotated to the position illustrated in Fig. 4 with the felt strip 18 tightly pressed against the floor 16 and the face of the door 10 thereby effectually closing the opening

between the bottom of the door and the floor against the passage of air currents. In addition, the device acts as a door check which prevents banging the door closed. It also eliminates annoying and sleep disturbing rattling of bedroom doors due to air currents from open bedroom windows.

When the door is opened, the shank of the hook 20 slides back through the eye. As the opening movement progresses, the spring expands and its compressional force decreases allowing the sealing member 17 to be rotated by the hook 20 in a counter-clockwise direction about the lower edge of the face 27a of the angle member. The expansion of the spring 26 continues to lift the sealing member 17 from the floor and force it away from the door until the door passes the nearly closed position illustrated in Fig. 3. Thereafter, the sealing member 17 is held by the spring 26 in a position well-above the floor as shown in Fig. 3 so that it does not drag or wipe against the floor as the door swings through the arc of its opening and closing movements. As a result, wear and loss of efficiency requiring replacement are effectually eliminated.

If the device is to be utilized on a door opening oppositely from that shown in the drawing, i. e., a right hand door instead of a left-hand door, it is only necessary to change the eye members 22, 23 to approximately diametrically opposite positions, as shown in Fig. 6. Alternatively, the eyes may be left in the positions illustrated and the angle member may be placed on the opposite end of the member 17.

Although in accordance with the provisions of the patent statutes, the principle of this invention and the best mode in which it is contemplated applying it have been explained, it will be understood that the embodiment shown and described is merely illustrative and that the invention is not limited thereto since alterations and modifications will readily suggest themselves to persons skilled in the art without departing from the true spirit of this invention or from the scope of the annexed claims.

What I claim as new and desire to secure by Letters Patent of the United States is:

1. An attachment to a member for closing an opening having a stop, comprising a sealing member, means for attaching said sealing member to said closing member comprising a hook member secured to said closing member and an eye member secured to said sealing member and cooperating with said hook member to provide movement of said sealing member with respect to said closing member, a spring member for moving said sealing member along the shank of said hook member and biasing said sealing member out of engagement with said closing member and with a part forming said opening and a member secured to said sealing member at one extremity thereof and arranged to engage said stop in response to the closing movement of said closing member for effecting rotary movement of said sealing member into engagement with said closing member and said part.

2. An anti-draft device for doors provided with the lateral stops comprising a rod member having a length substantially equal to the distance between said lateral stops, means for attaching said member to said door comprising a hook member secured to said door at a predetermined distance above said floor and an eye member secured to said rod member and cooperating

with said hook member to provide movement of said rod member with respect to said door, a spring surrounding the shank of said hook member for biasing said rod member out of engagement with said floor and the face of said door, and a member secured to said rod member at one extremity thereof and arranged to engage with one of said stops in response to the closing movement of said door for effecting rotary movement of said rod member into engagement with said floor and the face of said door.

3. A device for preventing the passage of air current through the space between the floor and the bottom surface of a dwelling house door and the like comprising a rod member having a length substantially equal to the distance between the door stops, said member being provided with a strip of fabric for engaging the face of said door and the surface of said floor to

seal said space, fastening means for said rod member comprising a hook member secured to said door at a predetermined distance above the floor and having a shank portion curving upwardly from the floor, an eye member secured to said rod member and cooperating with said hook member to provide for movement of said rod member with respect to said door, a pair of cup-shaped washers on said shank between said eye and the face of said door, a spring surrounding said shank between said washers for normally biasing said rod member out of engagement with said floor and said door, and an angle member secured to one extremity of said rod member for engaging one of said stops to rotate said rod member so that said fabric strip is actuated into engagement with said floor and said door.

STORRS M. BISHOP.
